BROOM HOLDER

Filed Jan. 17, 1930

J. C. Horn, INVENTOR
BY Victor J. Evans

ATTORNEY

UNITED STATES PATENT OFFICE

JOHN C. HORN, OF GLENKARN, OHIO

BROOM HOLDER

Application filed January 17, 1930. Serial No. 421,511.

This invention relates to broom holders and has as its general object to provide a device which may be suspended or hung upon a wall or other support and with which the handle of a broom or the like may be conveniently and quickly engaged and automatically grasped so as to be supported in suspended position thereby.

Another object of the invention is to provide a device for the purpose stated which may be made from sheet metal blanks at an exceptionally low cost, and which will be so simple in its construction as to adapt it to be manufactured at little expense, the invention 15 contemplating in this connection, a hinge connection between the fixed and the movable gripping member of the device which will consist of a sheet metal blank properly formed, and which blank will be anchored without the employment of screws.

This invention also consists in certain other features of construction and in the combination and arrangement of the several parts, to be hereinafter fully described, illustrated in 25 the accompanying drawing and specifically pointed out in the appended claims.

In describing my invention in detail, reference will be had to the accompanying drawing wherein like characters denote like or 30 corresponding parts throughout the several views, and in which:

Figure 1 is a view in front elevation of the broom holding device embodying the invention, a broom being shown suspended therefrom.

Figure 2 is a vertical sectional view illustrating the parts in position to clamp a broom handle.

Figure 3 is a top plan view of the device.

Figure 4 is a detail sectional view taken substantially on the line 4—4 of Figure 3.

The device embodying the invention comprises a fixed handle gripping and supporting member, which is formed from a single sheet metal blank and this member comprises an attaching portion 1 which is of approximately rectangular form and which is reinforced by overturned flanges 2 at its opposite vertical edges, and provided in its upper portion with an opening 3 whereby it may be

hung upon a nail or the like, indicated by the numeral 4. This member of the device further comprises a portion 5 which is likewise of rectangular form and which is integral with and extends forwardly at right angles from the lower end of the portion 1, the said portion 5 therefor outstanding from the wall or other support upon which the portion 1 is suspended. The portion 5 is reinforced at its lateral edges by overturned flanges 6 corresponding to the flanges 2 upon the portion 1, and is formed with a centrally located rectangular opening, indicated by the numeral 7. This opening is of a size greater than the diameter of an ordinary broom handle, and therefore, a broom handle may be inserted upwardly through the said opening, and, as best illustrated in Figures 3 and 4 of the drawing, the forward wall of the opening is beveled so as to provide a sharp biting edge 8, and the device further comprises a swinging member which is to have gripping engagement with that side of the broom handle opposite the side which is engaged by the member 1, and is formed from an integral sheet metal blank which is of general rectangular form except that in its forward side it is formed with a V-shaped recess, indicated by the numeral 10 and, at its rear side, is recessed at its intermediate portion as indicated by the numeral 11, and the portions at the opposite sides of the recess are overturned to provide pintle lugs indicated by the numeral 12.

These lugs 12 constitute one part of a hinge, and the other member of the hinge is formed from a sheet metal blank which is of general rectangular form, and which is bent to provide a substantially tubular pintle lug 13 located intermediate its two ends, the portions of the blank at opposite sides of the lug being brought in mutual contact as at 14, and the blank beyond its said portions, being formed with an upstanding portion 15, and a horizontal portion 16. The portions 14 of the blank between the pintle lug 13 and the portions 15 and 16 are fitted through a slot 17 formed substantially at the fold between the portions 1 and 5 of the first described blank, and a pintle pin 18 is fitted through the

100

aligned pintle lugs 12 and 13, and in this manner the member 9 is hingedly connected with the member 1, it being observed by reference to Figures 1 and 3 of the drawings that the pintle lugs 12 are held in the fold between the portions 1 and 5 of the first described blank by reason of the engagement of the pintle pin therethrough and through the pintle lug 13.

10 In order that the member 9 may be caused to normally assume a lowered position, lying flat upon the upper side of the member 5, a weight block 19 is secured by a rivet or otherwise to the upper side of the member 9 rearwardly of the V-shaped recess 10.

15 It will be observed by reference to the several figures of the drawing that the V-shaped recess is located above the forward portion of the opening 7, and it will be understood from the foregoing and by reference to the drawing, and particularly Figures 2 and 3, that when the broom handle is slid upwardly through the opening 7, it will ride not only against the sharpened edge or beveled wall 20 of the opening 7, but also against the side walls of the recess 10 in the member 9, and therefore the member 9 will be swung upwardly to assume substantially the position shown in Figures 2 and 3 of the drawing and, 25 when the broom handle is released, the walls of the recess 10 will engage the rear side of the broom handle at spaced points, and as the weight of the broom will then be more or less imposed upon the member 9, the said member will swing downwardly, and as it does so, the forward side of the broom handle will engage against the sharpened edge of the wall 8 of the opening 7 in the member 5, and this edge will bite into the handle of the 30 broom sufficiently to insure against any further downward displacement of the handle in the opening. Therefore, it is only necessary, in order to suspend a broom by the use of the device, to insert the handle of the broom upwardly through the opening 7 in the member 5 and then release the handle.

45 What I claim is:—

1. A broom holder comprising a fixed member including a suspension portion and a portion 50 extending at right angles thereto, the last mentioned portion being provided with an opening to accommodate the handle of a broom, and the front wall of the opening being straight and beveled to provide a biting edge, a member hinged in the angle between the first and second mentioned portions of the first mentioned member and designed, by gravity, to assume a position resting upon the upper side of the second mentioned portion of the first mentioned member, the said last mentioned member being provided with a V-shaped recess having beveled walls to engage that side of a broom handle opposite the 55 side engaged by the forward wall of the open-

ing in the second mentioned portion of the first mentioned member.

2. A broom holder comprising a fixed member including a suspension portion and a portion 60 extending at right angles thereto, the last mentioned portion being provided with an opening to accommodate the handle of a broom, and the front wall of the opening being straight and beveled to provide a biting edge, a member hinged in the angle between the first and second mentioned portions of the first mentioned member and designed, by gravity, to assume a position resting upon the upper side of the second mentioned portion of the first mentioned member, the said last mentioned member being provided with a V-shaped recess to engage that side of a broom handle opposite the side engaged by the forward wall of the opening in the second mentioned portion of the first mentioned member, the recess in the second mentioned member having relatively converging beveled side walls, whereby to provide for a three point engagement of the gripping portions of the two members, with the broom handle.

65 In testimony whereof I affix my signature.
JOHN C. HORN.
